UNITED STATES PATENT OFFICE

2,541,300

BOTTLE FEEDER

Anthony R. Silva, San Jose, Calif.

Application February 24, 1948, Serial No. 10,332

11 Claims. (Cl. 198—30)

1

The present invention relates to feeders for bottles and the like articles and is concerned more particularly with the provision of a feeder adapted to receive an irregular array or group of bottles and to arrange and discharge the bottles as a single file.

It is a general object of the invention to provide an improved feeder for bottles of the character employed in connection with filling machines and other equipment where a single file of bottles is required.

A further object of the invention is to provide a bottle feeder of the above character which is reliable in its operation and which will keep breakage of bottles at a minimum.

Another object of the invention is to provide feeders of the above character in which a continuous file of bottles is maintained at the discharge without gaps so that the equipment being supplied will always have the required number of bottles for operation.

A further object of the invention is to provide a feeder of the above character which can be readily adapted for operation with different sizes of bottles.

Other objects and advantages of the invention will be apparent from the following description of certain preferred embodiments thereof, as illustrated in the accompanying drawings, in which:

Figure 1 is a plan view of a bottle feeder employing the invention.

Figure 2 is a side elevational view of the feeder as indicated by the arrow 2 in Figure 1.

Figure 3 is a fragmentary side elevational view of the feeder as indicated by the arrow 3 in Figure 1.

Figure 4 is a fragmentary plan view similar to Figure 1 but illustrating another condition in the operation of the feeders.

Figure 5 is a fragmentary plan view of a modified form of the bottle feeder.

Figure 6 is a fragmentary side elevational view of the feeder shown in Figure 5.

In general the bottle feeder of the instant invention is in the form of a rotary main feed disk to which bottles are supplied in groups or in irregular array from an auxiliary feeder. A pair of opposed feed belts are disposed above the disk to direct and guide the bottles as they travel with the disk into a single file discharge. Also a reserve-supply of bottles is formed and maintained which is immediately available to fill in gaps in the discharge line.

Referring to the drawings, the machine includes a fabricated metal frame 10 (Figures 1 to

5) upon which the main feed disk 11 is mounted by means of a vertical drive shaft 12 suitably journaled on the frame. The drive shaft 12 is connected through suitable bevel gearing 13 and a chain and sprocket drive 14 with a drive motor 16 which may be of the variable speed type if desired. The main feed disk 11 rests upon the cross angles 10a at the top of the frame 10 and in general is divided into a feeding zone A for irregularly arranged bottles and a discharge zone B for bottles which have been arranged in single file. The discharge zone B is defined by respective conveyors 17 and 18 mounted above the disk 11 and providing a discharge path in which the disk 11 is traveling to effect a feed and control of the bottles for reliable continuous single file discharge as will be described hereinafter.

The general feed zone A is located adjacent an auxiliary feed disk 21 which is mounted upon an extension 22 of the main frame and overlaps the main feed disk 11. The desired close spacing of the feed disks at their overlapping portions is maintained by respective upper and lower sets of guide rollers 23 and 24 carried by the frame extension 22. As seen in Figures 1 and 2, the auxiliary feed disk 21 is carried by a shaft 26 on the auxiliary frame 22 and is connected by a chain and sprocket drive 27 to the main drive shaft 12 so that the auxiliary feed disk 21 is driven at a relatively lower speed than the main disk 11. In this way as bottles slide off of the auxiliary disk 21 onto the disk 11 they are quickly carried out of the way of any succeeding bottles being fed from the auxiliary disk.

To guide and control the flow of bottles on the auxiliary disk 21 and the main feed disk 11, an arcuate guide rail 31 is mounted on the frame extension 22 and extends about a portion of the feed disk 21. The guide rail 31 is joined at one end to the V-shaped end of a rail 32 which extends inwardly to the center of the disk 21 and then outwardly of the disk 21 and generally arcuately out over the main disk 11 as an extension 32a which is connected by a bracket 33 to a frame part of the machine. It will be seen that the extension 32a of the guide rail 32 has its end portion opposed to a portion of the conveyor 17 and terminates adjacent the conveyor 18. At its other end, the guide rail 31 is connected to a generally V-shaped guide rail 34 also suitably supported on the frame of the machine and serving to define a part of the peripheral edge of both the auxiliary feed disk 21 and the main feed disk 11. If desired, also an auxiliary feed rail 38 may be provided extending substantially radially

of the main disk 11 to guide bottles inwardly thereof as they pass from the auxiliary disk 21 onto the main feed disk 11.

From the above description it will be seen that cases of bottles can be placed on the auxiliary disk 21 and will be fed therefrom onto the main feed disk 11 which is rotating oppositely to the auxiliary feed disk 21 so that their overlapping edges are traveling in the same general direction. The auxiliary disk 21 is traveling at a relatively low rate of speed so as to avoid overturning of the bottles and to enable easy handling of the cases during unloading.

The conveyor 17 is the main feed control conveyor and is made up of a pair of vertically spaced belts trained about a set of idler pulleys 41 journaled on the shaft 12 above the disk 11 and separated by a boss 42 of a support bracket 43 for the conveyor 17. The pair of belts comprising the conveyor 17 are also trained about respective sets of spaced idler pulleys 44 and 46 suitably journaled in bosses of the bracket 43 and also about a set of driving pulleys 47 carried by a shaft 48 journaled in a boss 49 of the bracket 43. At its lower end the shaft 48 (Figure 2) carries a drive sprocket 51 engaged by a drive chain 52 which is trained about a drive sprocket 53 on the shaft 12.

The auxiliary feed control conveyor 18 (Figures 1, 2 and 3) also comprises a pair of vertically spaced belts trained about a set of idler pulleys 56 carried by a shaft 55 mounted at the end of a support arm 57 and a pair of driving pulleys 58 carried by a shaft 59 journaled on the frame and providing a pivotal mounting for the support arm 57. The shaft 59 carries a suitable sprocket 60 at its lower end which is engaged by the chain 52. An adjustable idler sprocket 61 is also provided for the chain 52. The arm 57 (Figures 2 and 3) carries a depending bracket 62 engaging a slotted arm 63 carried by the frame 10 and adjustably secured thereto by a bolt 64. By adjusting the conveyor 18 about its pivot axis the relative spacing between the conveyor 18 and the discharge stretch of the conveyor 17 can be adjusted.

Adjacent the end of the discharge path provided by the conveyors 17 and 18 an adjustable stop finger or arm 66 (Figures 1-3) is secured by a bolt 67 on the frame to engage the end bottle of a file of bottles engaged with the conveyor 18 to prevent their discharge so that only the file of bottles engaged by the conveyor 17 can be discharged over the ramp 68 onto the usual type of discharge conveyor 69.

It will be noted that the conveyor 17 has its stretch along the discharge path traveling in the same general direction as the direction of travel of the feed disk 11 except that the feed disk 11 in this portion of its path also provides a component of travel to the bottles 71 toward the conveyor 17. Correspondingly, the disk 11 will provide a component of travel of the bottles 71a engaged with the conveyor 18 away from this conveyor. It will also be noted that the conveyor 18 is driven so that its stretch along the discharge path travels in a direction opposite to the travel of the bottles and the general travel of the disk 11, but at a much slower rate than the travel of the opposed stretch of the conveyor 17. As a result the bottles 71a engaged with the conveyor 18 tend to rotate counterclockwise so that their side surfaces presented to the bottles 71 traveling in the main discharge path offer no resistance to the travel of these bottles.

The row of bottles 71a engaged with the belt 18 provide an auxiliary source or supply of bottles so that if a gap occurs in the file of bottles 71 traveling along the conveyor 17, a bottle 71a is fed directly from the file of bottles 71a (as shown in Figure 4) to fill the gap in the file of bottles 71. In this way a continuous single file discharge can be effected at a rate of feed sufficiently high for the usual type of filling and closing equipment.

It will be noted also that the conveyor 18 can be so adjusted with respect to the conveyor 17 to adjust the spacing therebetween to the diameter of bottle being used. The position of the conveyor 18 may also be adjusted so that it will be slightly flexed by the bottle during operation as shown in Figure 1. In this way the belt itself will tend to move bottles from the position 71a into a vacant position in the file of bottles 71.

20. In the form of the invention shown in Figures 5 and 6, the auxiliary feed disk 21 is replaced by an inclined ramp 76 which is supported on the frame 10 with its discharge end overlying the disk 11. The side rails 77 of the ramp 76 are slotted 25 to provide a guide for a pusher 78. The ends of the pusher 78 extend through the slotted side rails 77 and are engaged by respective operating arms or bellcranks 79 pivoted on a shaft 81 carried by suitable brackets 82 on the frame. At 30 their inner ends the arms 79 each carry a roller 83 engaged with a cam 84 under the influence of a spring 86. The cams 84 in turn are driven through a sprocket wheel 87 from the drive of the machine so that the pusher 78 is periodically reciprocated and then allowed to dwell in its retracted position so that another group of bottles can be deposited on the ramp 76 for feeding to the disk 11.

I claim:

40. 1. In a feeder for bottles and the like, a horizontally disposed rotatable disk, a pair of feed conveyors mounted above said disk in spaced-apart relation to provide therebetween a space for a double row of bottles, means for driving 45 said conveyors to provide opposite travel of the opposed stretches thereof, means for driving said disk to provide an outward component of movement to bottles in said space and a component of movement toward said conveyor stretch moving outwardly of said disk and away from the conveyor stretch moving inwardly of said disk, and a stop for a row of bottles on said space engaged with said inwardly moving stretch to prevent discharge thereof from said disk.

55. 2. In a feeder for bottles and the like, a horizontally disposed rotatable disk, a pair of feed conveyors mounted above said disk in spaced-apart relation to provide therebetween a space for a double row of bottles subject to discharging movement from said disk, means for driving 60 said conveyors to provide opposite travel of the opposed stretches thereof, and a stop for a row of bottles in said space engaged with the conveyor stretch moving inwardly of said disk to prevent discharge thereof from said disk.

65. 3. In a feeder for bottles and the like, a rotatable disk, a bottle guiding and feeding structure mounted above said disk to direct bottles deposited on said disk to a single file discharge path and including a conveyor forming one wall of said discharge path, said structure also including a second conveyor extending along said discharge path and spaced from said first conveyor 70 to provide an auxiliary file of bottles parallel to 75 to provide an auxiliary file of bottles parallel to

a file of bottles moving along said path, and a stop for said auxiliary file of bottles.

4. In a feeder for bottles and the like, a rotatable disk, a bottle guiding and feeding structure mounted above said disk to direct bottles deposited on said disk to a single file discharge path and including a conveyor forming one wall of said discharge path, means for driving said conveyor to effect movement of bottles outwardly of said path, said structure also including a second conveyor extending along said discharge path and spaced from said first conveyor to provide an auxiliary file of bottles parallel to a file of bottles moving along said path, a stop for said auxiliary file of bottles, and means for driving said second conveyor oppositely to said first conveyor and at a reduced speed therefrom.

5. In a feeder for bottles and the like, a rotatable disk, a bottle guiding and feeding structure mounted above said disk to direct bottles deposited on said disk to a single file discharge path and including a conveyor forming one wall of said discharge path, said structure also including a second conveyor extending along said discharge path and spaced from said first conveyor to provide an auxiliary file of bottles parallel to a file of bottles moving along said path, a stop for said auxiliary file of bottles, and feed means for delivering an array of bottles to said disk for controlled feeding by said bottle guiding and feeding structure.

6. In a feeder for bottles and the like, a horizontally disposed rotatable disk, a pair of feed conveyors mounted above said disk in spaced-apart relation to provide therebetween a space for a double row of bottles, one of said conveyors being mounted for movement with respect to the other of said conveyors adjacent the periphery of said disk to vary said space, means for driving said conveyors to provide opposite travel of the opposed stretches thereof, means for driving said disk to provide an outward component of movement to bottles in said space and a component of movement toward said conveyor stretch moving outwardly of said disk and away from the conveyor stretch moving inwardly of said disk, and a stop for a row of bottles in said space engaged with said inwardly moving stretch to prevent discharge thereof from said disk.

7. In a feeder for bottles and the like, a horizontally disposed rotatable disk, a pair of feed conveyors mounted above said disk in spaced-apart relation to provide therebetween a space for a double row of bottles, means for driving said conveyors to provide opposite travel of the opposed stretches thereof at a differential rate with the stretch moving in opposition to the movement of said disk travelling at a lower rate of speed than the other stretch, means for driving said disk to provide an outward component of movement to bottles in said space and a component of movement toward said conveyor stretch moving outwardly of said disk and away from the conveyor stretch moving inwardly of said disk, and a stop for a row of bottles in said space engaged with said inwardly moving stretch to prevent discharge thereof from said disk.

8. In a feeder for bottles and the like, a horizontally disposed rotatable disk, means for feeding bottles to said disk, a feed conveyor extending over the disk to the central portion thereof and providing a conveyor stretch travelling inwardly with respect to said disk and facing the portion thereof for receiving bottles and a discharge conveyor stretch travelling outwardly of

the disk and defining one side margin of a single file discharge path for bottles, a control conveyor mounted adjacent one edge of said disk and having a control stretch spaced from said discharge conveyor stretch at a distance corresponding substantially to twice the diameter of a bottle, said respective feed and control conveyors providing a diverging entrance for bottles carried by said disk during rotation thereof, and said control conveyor stretch being disposed over a portion of the disk path in which the disk is moving away from the discharge end of the control conveyor stretch, a stop for a row of bottles engaged with said control conveyor, and means for driving said control conveyor to cause said stretch thereof to travel from the discharge toward the feed end of said discharge path.

9. In a feeder for bottles and the like, a horizontally disposed rotatable main disk, means for rotating said disk, a pair of feed conveyors mounted above said disk in spaced-apart relation to provide therebetween a space for a double row of bottles, means for driving said conveyors to provide opposite travel of the opposed stretches thereof, means including an auxiliary disk for feeding bottles to said first-named disk, means for rotating said auxiliary disk in a direction opposite to the rotation of said main disk, guide means related to said main disk to carry said bottles to the entrant opening of said space, the rotation of said main disk providing an outward component of movement to bottles in said space and a component of movement toward said conveyor stretch moving outwardly of said main disk, and a stop for a row of bottles in said space engaged with said inwardly moving stretch to prevent discharge thereof from said main disk.

10. In a feeder for bottles and the like, a horizontally disposed conveying means, a pair of feed conveyors mounted above said conveying means in spaced apart relation to provide therebetween a space for a parallel double row of bottles subject to discharging movement from said conveying means, means for driving said conveyors to provide opposite travel of the opposed stretches thereof, and a stop for the row of bottles in said space engaged with the conveyor stretch moving inwardly of said conveying means to prevent discharge thereof from said conveying means.

11. In a feeder for bottles and the like, conveying means, a bottle guiding and feeding structure mounted above said conveying means to direct the bottles deposited on said conveying means to a single file discharge path and including a first conveyor forming one wall of said discharge path, said structure also including a second conveyor extending along said discharge path and spaced from said first conveyor to provide an auxiliary file of bottles parallel to the file of bottles moving along said path, and a stop for said auxiliary file of bottles.
